PERMITIT COMPANY, OF NEW YORK, N. Y., A CORPORATION OF DELAWARE.

WATER-SOFTENING APPARATUS.

1,303,679.

Specification of Letters Patent. Patented May 13, 1919.

Application filed October 17, 1914. Serial No. 367,119.

To all whom it may concern:

Be it known that I, Cass L. KENNICOTT, a citizen of the United States, residing at Chicago Heights, in the county of Cook and State of Illinois, have invented a new and useful Improvement in Water-Softening Apparatus, of which the following is a specification.

My invention relates to improvements in water-softening apparatus and methods of adjusting and regulating the same, and, more particularly, to the construction and adjustment of the chemical feeding and regulating mechanism used with such apparatus.

The objects of the invention are: to provide a form of feeding and regulating device by the use of which the chemical re-agents most commonly used in water-softeners may be handled in the dry state; to provide in connection with the feed-regulating devices a mechanical calculating device by which the setting of the regulating levers may be determined; to provide indicating scales co-operating with the regulating levers and by which the exact proportions of each chemical which is being fed are determinable from a mere inspection of the regulator; to provide a method of adjusting the regulators directly from the statement of analysis of the raw water; and, in general, to improve the construction and increase the efficiency of apparatus of this character and to provide a simple and accurate method of ascertaining and effecting the necessary adjustment of the apparatus. Further objects and advantages of the invention will appear from the following detailed description of the same, reference being had to the accompanying drawings, in which:

Figure 1 is a general diagrammatic view of a water-softening apparatus embodying the features of construction of the invention and adapted for adjustment according to the method of the same, parts being shown in elevation and parts in section. Fig. 2 is a detail plan view of the dividing box of Fig. 1; Fig. 3 is an enlarged detail in elevation of the clutch mechanism of Fig. 1; Fig. 4 is a section in the line 4 of Fig. 3; Fig. 5 is an enlarged section of the feeding mechanism, taken on the line 5 of Fig. 1; Fig. 6 is a cross-section of Fig. 5, taken on line 6; Fig. 7 is an enlarged sectional view of a modified form of feeding mechanism; Fig.

8 is an enlarged section of a further modification of the feeding mechanism; Fig. 9 is a plan view of the feeding roller shown in Fig. 8; Fig. 10 is a plan view of another modified form of the feeding mechanism, 60 Fig. 11 is a diagrammatic view in elevation of a modified form of water-softening apparatus, Fig. 12 is a front elevation showing a form of slide rule and calculating device, adapted for use with this apparatus, by 65 which the proportions of the chemicals fed to the water may be determined, and Fig. 13 is a central vertical section of same.

Referring to the drawings, 11 indicates the raw-water supply-pipe, provided with a 70 valve 12 which is automatically controlled as will later appear. Through the pipe 11 the water discharges into the rear compartment 14 of a dividing box 13, and is then split up into two streams, a main stream which passes 75 through the large V-notch 17 in the partition 18, and thence into the compartment 19, discharging finally through an aperture 20 into the water-wheel casing 21, and a smaller or regulating stream which passes through 80 the small V-notch 22 into the compartment 23 and thence out through the pipe 24. In the water-wheel casing is mounted an over-shot-wheel 25 which receives the main stream 85 of raw water and is actuated thereby to provide the small amount of power needed to operate the moving parts of the apparatus. From a well 26, at the bottom of the water-wheel casing, the raw water discharges 90 through the spout 27 into a mixing basin 28. The basin is supported, as by the H-beams 29, in the upper end of a large sedimentation tank 30, which serves both as a precipitating 95 and purifying reservoir and as a holder for the treated water. Outlet from this tank to the boiler-feed line is by some suitable off-take aperture, not shown. Within the sedimentation tank and floating on the surface of the water therein is a controlling float 31', which, by means of the connecting link 32', 100 is coupled to the raw-water supply-valve 12, so that as the treated water is drawn from the sedimentation tank, the fall of the float will open the valve 12 and set the apparatus in motion to treat a further supply of raw 105 water.

The chemical feeding and regulating apparatus to which my invention more particularly relates comprises the following 110 combinations of mechanism. Directly above

the basin 28 and in position to discharge thereinto by gravity, are a pair of hoppers 31, 32, which serve as containers for the dry chemicals, for example, hydrated lime and 5 soda ash, which are to be fed to the water. These hoppers and the regulating devices thereof are exact duplicates of each other and, therefore, a description of one will 10 serve for both. Each hopper is provided with a conical-shaped bottom-funnel 33 which terminates in a discharge spout 34 (see Fig. 5), the end of the discharge spout being so formed as to closely fit the cylindrical surface 35 of a feed-roller 36. It 15 will be noted from Fig. 5 that the front end or face of the discharge spout lies in a vertical plane passing through the axis of the roller. In this front face is formed the feed aperture 37, which is controlled by a 20 slide 38 closely fitting the flat face of the spout and held in engagement therewith by the tongue and groove connection 39. Each of the slides 38 is controlled by a link connection designated 40 and 41, respectively, 25 for the hoppers 31 and 32. In order to permit of the vertical straight line motion of the regulating slides 38, the links 40, 41 are shown as floating links, the outer end of each being secured to an oscillating lever 42, 30 while the inner ends are connected by means of the vertical links 43 to the calculating and regulating mechanism 44. The construction and operation of this latter mechanism will be described in connection with 35 the description of the operation of the machine.

The feed-rollers 35 are mounted on a horizontally journaled shaft 45, which is driven by a pair of miter gears 46 from the vertical 40 shaft 47. The shaft 47 is in turn driven through a miter gear connection 48 from the horizontal shaft 49 of the water-wheel 25, a clutch-mechanism, indicated generally by 50, being interposed between the driving 45 and driven ends of the shaft 47. Bevel gears 51, 52 and 53 on the water-wheel shaft 49 are used to drive agitator shafts 54 and 55 extending vertically through the hoppers 31 and 32, respectively, and the stirrer shaft 56 which extends down between the hoppers and terminates in a propeller or stirrer 57 located in the bottom of the basin 28. The agitators mounted on the shafts 54 and 55 are not shown, as they may be of 55 any conventional form and may operate in a well understood manner to constantly agitate and keep broken up the dry chemicals within the hoppers 31 and 32.

The clutch mechanism, indicated generally by 50, is shown in detail in Figs. 3 and 4, and comprises ratchet clutch members 60 and 61, respectively secured to the upper and lower ends of the shaft 47. The clutch member 60 is secured by a simple pin connection, 60 indicated at 62, while the clutch member 61

is splined or otherwise mounted for longitudinal movement upon the lower half of the shaft 47. A collar 63 is pinned to the shaft some distance below the clutch member 61, and interposed between this collar and the clutch member is a compression spring 64, which constantly urges the clutch member 61 toward the mating clutch member 60. In order to hold the clutch member 61 in its normal position out of engagement with the 70 clutch member 60, I provide a bell crank lever 162, journaled at 163 upon some part of the frame of the machine and having an inclined foot-plate 164 formed on one end and engaging a pin 65 secured in the periphery of the clutch member 61. The bell crank 162 is operated by the link 63', which in turn is connected to a lever 64' (Fig. 1) pivoted at 65' upon an arm secured to the bucket tank 66. Within the bucket tank is 80 journaled an automatically-acting tipping-bucket 67, having a V-shaped bottom 68 and divided into two bucket compartments by a vertical partition 69, which also serves as a diverter for the water stream and as an 85 operating means for the lever 64' as will appear. Stops 70 and 71 are secured to the sides of the bucket-tank and form rests to limit the oscillatory movement of the bucket 67. The pipe 24, through which the regulating stream from the dividing box flows, terminates in a down-turned end 72 which discharges directly above the trunnion of the tipping bucket 67. The outlet from the bucket tank is through a pipe 73 which discharges into a funnel 74 and thence into the mixing basin 28. The funnel 74 serves to positively direct the chemicals fed from the hoppers 31 and 32 into the mixing basin 28.

The operation of the apparatus so far 105 described is as follows:

When treated feed water is drawn from the sedimentation tank 30, the level therein will drop, causing the float 31' to fall and carry with it the link 32', thus opening the 110 raw-water supply-valve 12 and permitting the raw water to discharge through the spout 11 into the dividing box 15. From this box the water flows in two streams, a main stream which passes over the water 115 wheel 25 and actuates the same and a regulating stream which passes out through the pipe 24 to the tipping bucket 67. The rotation of the water wheel shaft 49 is caused to operate the agitating and stirring devices 52, 53, 51, as set forth, and further serves to rotate the clutch member 60 secured to the upper end of the vertical shaft 47. Assuming that the parts are in the position shown in Fig. 1, it will be seen that the 125 regulating stream of water which issues from the down-turned end 72 of the pipe 24 will impinge against the right-hand side of the partition 69 of the bucket 67, and will, therefore, gradually fill up the right- 130

hand compartment of the bucket. When the right-hand compartment of the bucket becomes sufficiently filled, the bucket will tip to the right until it rests upon the stop 71, 5 and in this movement the upper end of the partition 69 will have rocked the lever 64, causing the lever to ascend to a maximum height as the partition 69 reaches a vertical position and then to drop to its minimum 10 height as the partition assumes an inclination opposite to that shown in the drawing. The oscillation of the lever 64 will be transmitted through the link 63 to correspondingly oscillate the bell crank lever 162, and, 15 as shown in Fig. 3, this oscillatory movement of the bell crank lever will move the foot-plate 161 of the same out of contact with the pin 65 in the lower clutch member 61, thus permitting the compression spring 64 to 20 force this clutch member into engagement with the teeth of the upper clutch member. Such engagement of the clutch members will cause the lower section of the vertical shaft 47 to revolve and through the miter gears 25 46 the horizontal shaft 45 carrying the feed-rollers 35 will be caused to correspondingly revolve. Referring to the Fig. 5, it will be seen that a certain regulated amount of the dry chemical which rests upon the face of 30 the feed-roller will, by this movement, be caused to pass out through the aperture 37. As the apparatus is shown, the shaft 47 can make but a single revolution at one time, for immediately after the bell crank 162 is oscillated to the right, the drop of the lever 64 will return it to its original position, and so as the pin 65 approaches its original position, it will engage beneath the inclined 35 surface of the foot 161 and continued rotation of the shaft will move the pin along this incline, thus forcing the lower clutch member downward, until by the time the pin has reached the position shown in Fig. 3, the clutch teeth are completely out of engagement. 40 A single tipping movement of the bucket 67 therefore operates to engage the clutch for a single revolution, at the end of which it becomes automatically disengaged. For each tipping movement of the 45 bucket, therefore, the feed rolls 35 will have revolved some pre-determined amount, dependent upon the ratio of the miter gears 46. The tipping of the bucket, in turn, is dependent upon the flow of water from the 50 dividing box, that is to say, the time it takes for the bucket to fill sufficiently to tip is a function of the rate of flow of the raw water through the pipe 11. It will be understood that after the bucket has tipped to the right, 55 the partition 69 will serve to direct the regulating stream of water into the left-hand compartment of the bucket and thus cause it to tip to the left. The operation of the bucket is, therefore, an intermittent oscillation, dependent in time upon the rate of 60

flow of the water through the pipe 72. It will thus be understood that the revolution of the feed rolls 35, by which is determined the feed of the dry chemicals is in direct proportion to the feed of raw water through 70 the pipe 11.

The second factor determining the relation between the feed of raw water and the feed of the chemicals from each receptacle, 75 is the height of the opening 37 through which the chemicals are fed, and my invention is largely concerned with a means for adjusting these openings. Mounted on some conveniently accessible part of the frame-work and as shown directly in front of the hoppers 31, 32 is the mechanical calculating, indicating and feed-regulating mechanism, generally indicated by the numeral 44. This mechanism comprises three concentric disks 80, 81 and 82, and a pair of combined regulating levers and pointers 83 and 84, journaled to oscillate about an axis concentric with that of the disks, and connected to the links 43 by which the levers 40, 41, controlling the sliding gates are moved. 85

In the treatment of raw water to render it suitable for boiler-feed purposes, it will be found, in general, that the pertinent characteristics of the water may be grouped under two or three headings. For example, 90 the following grouping is found to be satisfactory for the purposes of the art:

(1) Hardness—*i. e.*, the number of parts per 100,000 of calcium and magnesium salts contained in the water. 95

(2) Alkalinity—*i. e.*, the number of parts per 100,000 of carbonates contained in the water.

(3) Causticity—*i. e.*, the character and amount of the hydrates and $\frac{1}{2}$ the normal 100 or mono carbonates contained in the water, per 100,000 parts.

In the analysis of the water, therefore, we need only concern ourselves with these few pertinent characteristics and a statement of 105 the analysis, for our purposes, will therefore consist merely of the name of each characteristic, or some group heading similar to that given in the example as causticity under which a number of characteristics are 110 expressed, each name followed by a numeral which forms a quantitative measure of the corresponding characteristic. Assuming that such an analysis has been made and a statement prepared in the manner I have 115 indicated, it is my intention to so construct the calculating and indicating devices, indicated generally by 44, to the end that the analysis statement alone will serve as a 120 guide by which the exact setting of the regulating levers 83 and 84, and their connected regulating slides or gates 38 may be accomplished. With this in view the scales 80, 81 and 82 are so graduated as to form a mechanical calculating device or slide-rule, and 125 130

to this end the scales 80 and 82 which I will denote the chemical scales are graduated in terms indicating masses or volumes of chemicals, while the intermediate scale 81 is graduated in terms expressing quantitatively the pertinent characteristics of the raw water. Thus in the specific embodiment of the invention shown, the chemicals employed are hydrated lime and soda ash, contained, respectively, in the hoppers 31 and 32. The regulating lever 84 is connected to the gate 38 which regulates the feed aperture of the soda-ash hopper, and therefore the stationary scale 80 with which the pointer formed on the lever 84 co-operates is graduated in terms indicating pounds of soda-ash, while the scale 82 with which the pointer on the regulating lever 83 co-operates is graduated in terms indicating pounds of lime, the sliding gate 38 at the bottom of the lime hopper being connected with this regulating lever.

The movable scale element will have a series of graduations for each of the characteristics of the water, for instance, hardness, alkalinity and causticity, these graduations being so related to the chemical scales that the hardness series co-operates with the soda scale, and the causticity series with the lime scale. The exact construction and graduation of a slide-rule or calculating device of this type is shown in Figs. 12 and 13. In this form of the slide-rule there is an outer stationary scale 80 graduated in terms of weights of lime necessary for treating a unit of raw-water. Concentric with the outer fixed scale is a second annular scale 81, having three sets of peripheral graduations, an outer set of graduations indicated by the numeral 85 and expressing the causticity of the water, a central series of graduations indicated by 86 and expressing the alkalinity of the water, and an inner series of graduations 87, expressed in terms of the hardness of the water. Located centrally within the movable scale 81 is a second fixed scale 82 having along its edge graduations expressing weights of soda ash necessary for treating a unit charge of raw-water.

In order to illustrate the operation of my slide-rule, we will assume the following sample analysis of raw-water:

Causticity	0
Alkalinity	8
Hardness	10

The movable scale 81 will be shifted to the right until the eighth graduation of the alkalinity series is in radial alignment with the zero marks of the soda and lime scales. Opposite the zero graduation of the causticity scale will be found a mark indicating 10% ounces of lime, and opposite the tenth graduation of the hardness scale will be found a mark indicating 8 ounces of soda.

A proper unit charge for raw-water of the above character will, therefore, consist of 10% ounces of lime and 8 ounces of soda-ash per thousand gallons of water to be treated. The regulating levers 83, 84, will then be moved until their respective pointers coincide with the graduations on the lime and soda scales thus determined, and this movement of the regulating levers will so adjust the sliding gates 38 as to permit of the feed of the requisite quantity of each chemical. It is apparent that with the device so constructed the pointers upon the indicating levers will always show directly upon their respective scales the relative proportions of lime and soda which are being added to each unit charge of water which passes through the apparatus. The connections between the regulating levers 83, 84, and their respective sliding gates must, of course, be designed so that the proper movement of the gate will result from any definite setting of the levers. I have shown a simple crank and link connection for the gate and by experiment found that such simple connection will give a fair degree of accuracy of adjustment. It will be understood, of course, that the aperture 37 need not vary in cross-sectional area in direct proportion to the movement of the gate. Thus, these apertures may have inclined or curved side walls, fixed or adjustable, and by such construction the effective opening of the feed apertures 37 for any given setting of the regulating levers may be conveniently altered without recourse to complicated cam or linkage connections between the regulating levers and the gate.

As the hydrated lime and soda is fed from the rollers 35, it falls by gravity into the funnel 74 and is, by the latter, directed into the bottom of the basin 28, there mixing with the main stream of raw water which issues from the spout 27 and with the regulating stream which discharges from the pipe 73. The raw water and the lime and soda are stirred by the propeller 57 and thus become thoroughly mixed before overflowing from the basin 28 into the sedimentation tank. In the latter tank the impurities from the water are precipitated and the treated feed-water is stored. The form of feed-regulating apparatus which I have shown, i. e., the cylindrical feed rollers and the gates controlling the feed apertures above the same, is peculiarly adapted for handling chemicals, such as hydrated lime and soda ash in the powdered or palverulent form, and also lends itself most readily to the combination with the mechanical calculating and indicating devices, by which I adjust the feed of the chemicals.

In Figs. 7 to 10, inclusive, I have shown various modifications of feeding mechanism adapted to handle chemicals such as lime

and soda ash in the dry state. In Fig. 7, I have shown the feed rollers 35 replaced by endless belts, denominated 90, and passing over drums 91, either or both of which may be driven through the shaft 47 to move the belt proportionately to the supply of raw water. No change need be made in the construction of the hoppers 31 or 32 in order to adapt them to this form of belt-feeding device, except that the discharge spout 34 will, of course, be formed flat upon the bottom in order to accurately fit the upper face of the feeding belt 90.

In Figs. 8 and 9, I have shown a peculiar form of feed roll 92, having its surface grooved, as shown at 93, to provide a plurality of pockets which act to measure out definite charges of the chemicals. To co-operate with this form of feed roll, I use a discharge spout having a wedge-shaped end 44, as shown in Fig. 8 and to regulate the size of each unit charge or pocketful of the chemicals, I provide the rollers 92 with sliding caps 95, extending from the inner ends 25 of which are arms 96 corresponding in number to the number of pockets or grooves in the roll and having cross-sections of such form as to exactly fill the pockets of the roll, so that the latter presents a smooth exterior 30 surface. In this form of construction the regulating link 43 should shift the cap 95 axially of the feed roll 92, and thus move the arms 96 into and out of the grooves of the roll, thereby changing the effective 35 length of each pocket to correspondingly alter the quantity of chemical discharged at one revolution of the feed roll.

In Fig. 10, I have shown a still further modification of the feed mechanism, this 40 modification comprising a single feed disk 97, which is adapted to be mounted upon the vertical stirrer shaft 56 or upon any shaft similarly located between the feed hoppers 31 and 32. In this form of feed 45 mechanism a plain open-ended discharge spout will be used on each of the hoppers, similar to the spout illustrated in Fig. 7, and controlled by a sliding gate of the construction shown in Figs. 5 and 6. In order to 50 scrape off the chemicals as they are fed on to the rotating disk 97, I provide a pair of scraper bars 98, which are secured to the frame of the machine by any appropriate means, as by a web 99 surrounding the shaft 55 of the disk and secured to the journal which carries the same.

In Fig. 11 I have shown a modified form 55 of the feeding apparatus, in which the feed rollers are driven directly and constantly from the water-wheel-shaft, the adjustment of the apparatus being effected by adjusting the speed of the rolls with relation to the speed of the water-wheel-shaft. In this form of mechanism the structure has been

simplified by the omission of the dividing box and tipping bucket.

Referring to Fig. 11, I provide the usual sedimentation tank 30, float 31', raw-water supply-pipe 11, water-wheel-casing 21, water-wheel 25, water-wheel-shaft 49, hoppers or containers for dry chemical 31, 32, mixing basin 28 and associated structure, all substantially as shown in Fig. 1. In this modification, however, the raw-water supply-pipe 11 discharges directly into the 75 water-wheel-casing without the interposition of any dividing box, so that the whole of the water supply passes over the wheel. On the water-wheel-shaft 49, I provide bevel gears 200, 201 driving, respectively, the vertical shafts 202, 203. At the foot end of each of these shafts is mounted a friction disk, designated 204, 205, respectively, for the two shafts and co-operating with each friction disk is a slideable friction drum. The 80 drums designated 206, 207 are splined to the shafts 208, 209, respectively, of the feed rolls 210, 211. The friction drums may be shifted lengthwise of their shafts to move across the faces of the friction disks, whereby, the relative rotations of the drive-shafts 202, 203 and the roll shafts 208, 209 may be varied. To provide for the adjustment of the parts, I mount bell-cranks 212, 213, in a suitable location and these bell-cranks communicate 85 motion from the control links 43 of the regulating levers 33, 34, so that the angular movement of the regulating levers will cause the friction drums to be shifted across the faces of the friction disks.

The operation of the modified structure described above is as follows:

Raw water being supplied through the pipe 11 causes the water-wheel 25 to rotate, such rotation bearing a constant relation to 105 the volume of raw water supplied. The angular velocity of the water-wheel-shaft 49 will, therefore, be a function of the flow of raw water. Through the bevel gears 200 and 201, the vertical shafts 202, 203 will be 110 caused to revolve at the same speed as the shaft 49, and the friction drive connections at the bottoms of these shafts will operate the feed rolls 210 and 211 at a speed corresponding to and regulated by the volume 115 of flow of raw water. The first essential of the regulating action is, therefore, met by this construction, *i. e.*, the direct connection between the water-wheel-shaft and the feed rolls causes the latter to revolve proportionately to the flow of raw water and the feed of dry chemicals from the hoppers or containers will, therefore, be automatically rotated in proportion to the raw water supply and without the interposition of a dividing box or tipping bucket or any other mechanism. The adjustable friction drive connection between the vertical shafts and

the shafts of the feed rollers meets the second necessary feature of the regulation. By this connection the quantity of chemical fed from each container per unit of raw water supplied may be adjusted from the regulating levers 83, 84, which, by their link connections with the bell-crank 212, 213, shift the friction drums to vary the relative velocity of the feed rolls. In this form of the apparatus, therefore, I have also provided a simplified construction in which the feed of dry chemical is proportioned to the feed of raw water, and provided additional regulating means combined with the calculating means and acting to vary the proportion of each chemical fed in accordance with the quality of the raw water.

In connection with the construction shown in Fig. 1, it will be understood here, also, the dividing box and tipping bucket mechanism might be dispensed with, and the shaft 45 of the feed rolls driven constantly from the water-wheel-shaft 49, as illustrated in Fig. 11.

While I have shown and described, in considerable detail, various forms of water-softening apparatus adaptable for adjustment according to my improved method, it is to be understood that the invention is not to be construed as limited by anything herein contained, except in so far as such limitations are included in the appended claims.

I claim as new and desire to secure by Letters Patent—

1. In a water-softening apparatus, and, in combination, means for supplying raw water, a dividing box into which said raw water discharges, means in said dividing box for separating the raw water supply into a main stream and a regulating stream having definite relation to each other, a water motor positioned to receive the discharge of said main stream, a tipping bucket positioned to receive the discharge of said regulating stream, hoppers for containing a supply of dry chemicals, agitating means within said hoppers, means for driving said agitating means from said water motor, mechanical feeding devices for feeding chemicals from said hoppers, means for driving said feeding devices from said water motor, and means operated by said tipping bucket for regulating the action of said driving means.

2. In a water-softening apparatus, and, in combination, means for supplying raw water,

means for dividing the supply of raw water into a main and a regulating stream, a water motor adapted to be actuated by said main stream, a tipping bucket mechanism adapted to be operated by said regulating stream, chemical supply hoppers, mechanical feeding devices for feeding from said hoppers, means for driving said feeding devices from said water motor, and means connected with said tipping bucket for regulating the action of said driving means.

3. In a water-softening apparatus, and, in combination, means for supplying raw water, means for dividing the supply of raw water into main and regulating streams, a water motor adapted to be actuated by said main stream, a tipping bucket mechanism adapted to be operated by said regulating stream, hoppers for containing a supply of dry chemicals, discharge spouts connected with said hoppers in position to receive a gravity discharge of chemicals therefrom, said discharge spouts being formed with connected side and bottom openings, feeding rollers associated with said bottom openings, sliding gates associated with said side openings, means for driving said feeding rollers from said water motor, means operated by said tipping bucket mechanism for regulating said driving connection, adjusting levers for fixing the position of said sliding gates, indicating scales operatively related with said adjusting levers and graduated in terms expressing the proportion of chemicals supplied, and a calculating scale member operatively related to said indicating scale members and graduated in terms expressing the characteristics of the raw water.

4. In a water-softening apparatus, and, in combination, means for supplying raw water, means for dividing the supply of raw water into a main and a regulating stream, a water motor adapted to be actuated by one stream, a metering device adapted to be operated by said other stream, chemical supply hoppers, mechanical feeding devices for feeding from said hoppers, means for driving said feeding devices from said water motor, and means connected with said metering device for regulating the action of said driving means.

CASS L. KENNICOTT.

In presence of—

R. S. ELLIS,
H. C. ALGER.
